DESIGN FOR AN ADJUSTABLE FLUORESCENT LIGHTING FIXTURE

Carl Nitardy, New York, N. Y., assignor to Sylvania Electric Products Inc., Salem, Mass., a corporation of Massachusetts

Application September 15, 1945, Serial No. 122,112
Term of patent 14 years

(Cl. D48—20)

To all whom it may concern:

Be it known that I, Carl Nitardy, a citizen of the United States, residing at New York, in the county of Kings and State of New York, have invented a new, original, and ornamental Design for an Adjustable Fluorescent Lighting Fixture, of which the following is a specification, reference being had to the accompanying drawing, forming part thereof.

Figure 1 is perspective view of an adjustable fluorescent lighting fixture, showing my new design;

Figure 2 is a rear elevational view of the fixture; and

Figure 3 is a cross-sectional view looking up taken on line 3—3, Figure 2.

I claim:

The ornamental design for an adjustable fluorescent lighting fixture, as shown and described.

CARL NITARDY.
